(57) **CLAIM**

The ornamental design for a footing platform assembly for working, as shown and described.

DESCRIPTION

FIG. 1 is a front elevational view of the footing platform assembly for working in a condition that a pair of safety poles and the safety guardrail frames are provided on each of the front and rear sides of the platform part;

FIG. 2 is a top view thereof;

FIG. 3 is a bottom view thereof;

FIG. 4 is a right side elevational view thereof; and,

FIG. 5 is a perspective view of the footing platform assembly for working in a condition that a pair of safety poles and the safety guardrail frames are provided on each of the front and rear sides of the platform part.
